UNITED STATES PATENT OFFICE.

ALFRED SUEUR, OF NEW YORK, N. Y., ASSIGNOR TO M. J. PAILLARD & CO., OF SAME PLACE.

MUSIC-BOX.

SPECIFICATION forming part of Letters Patent No. 363,774, dated May 24, 1887.

Application filed April 15, 1886. Serial No. 198,932. (No model.)

To all whom it may concern:

Be it known that I, ALFRED SUEUR, of the city, county, and State of New York, have invented certain new and useful Improvements 5 in Music-Boxes, of which the following is a specification.

This invention relates to certain new and useful improvements in music-boxes in which the pin-cylinder is revolved by means of a 10 spring; and the object of my invention is to produce a music-box in which the pin-cylinder is revolved for a long time without requiring rewinding of the spring.

The invention consists in a base-plate provided on its under side with a large spring, 15 from which spring the motion is transmitted to the pin-cylinder.

In the accompanying drawings, Figure 1 is 20 a plan view of the under side of the base-plate of my improved music-box, showing the bridge and transmitting-wheels. Fig. 2 is a longitudinal view of the box. Fig. 3 is a plan view of the under side of the base-plate, the spring and other parts being removed. Fig. 4 is a 25 longitudinal section of the same on line $x x$, Fig. 3.

Similar letters of reference indicate corresponding parts,

The barrel A is formed on the under side of 30 the base-plate B, that is cast or otherwise made integral with the same; but it may be fastened by suitable devices. Two pillars, C C, also project from the under side of the base-plate B, the free ends of the pillars being a 35 short distance beyond the edge of the barrel, as shown in Figs. 2 and 4. A large spiral spring is placed in the barrel, and is fastened to the side of the same and to the spring-shaft D, said shaft D being journaled in the base- 40 plate and in the bridge E, secured to the pillars C.

A pinion, F, driven from the mainspring

shaft gears with the pinion or cog-wheel G, mounted on a shaft, H, journaled in the base-plate and on the bridge between one of the 45 pillars and the side of the barrel. Said shaft H carries a bevel cog-wheel, J, engaging with a bevel cog-wheel, K, on the pin-cylinder L. The pin-cylinder is thus revolved from the 50 spindle of the mainspring.

As a large mainspring can be used, the cylinder runs a long time without requiring the rewinding of the spring.

I am aware that music-boxes have been made in which a spring-barrel is made integral with 55 the base-plate, and I am also aware that music-boxes have been made in which a spring in an ordinary barrel has been arranged below the base-plate, and this I do not claim, broadly.

Having thus described my invention, I claim 60 as new and desire to secure by Letters Patent—

1. A music-box having a spring-barrel on the under side of the base-plate, combined with a spring in said barrel, said spring uncoiling 65 and in a plane parallel with that of the face-plate, and the spindle of said spring being at right angles to the base plate, substantially as shown and described.

2. A music-box having a spring-barrel and two pillars on the under side of the base-plate, 70 said barrel and pillars being made integral with the plate, combined with a spring in said barrel, the spring uncoiling in a plane parallel with that of the face-plate, and the spindle of said spring being at right angles to the base- 75 plate, substantially as shown and described.

In testimony that I claim the foregoing as my invention I have signed my name in presence of two subscribing witnesses.

ALFRED SUEUR.
